UNITED STATES PATENT OFFICE.

WILLIAM W. CASE, OF FRENCHTOWN, NEW JERSEY, ASSIGNOR TO WILLIAM H. FULPER, OF FLEMINGTON, NEW JERSEY.

CENTRIFUGAL GUN.

1,357,028.

Specification of Letters Patent. Patented Oct. 26, 1920.

Application filed October 17, 1917. Serial No. 197,015.

To all whom it may concern:

Be it known that I, WILLIAM W. CASE, a citizen of the United States, residing at Frenchtown, in the county of Hunterdon and State of New Jersey, have invented 5 certain new and useful Improvements in Centrifugal Guns, of which the following is a specification.

My invention is what may be termed a 10 centrifugal gun and the objects of the invention are to provide simple and effective mechanism for employing centrifugal force as the agent for hurling projectiles.

Special objects are to hurl projectiles with 15 great force and in a practically continuous stream. A further object is to enable ready aiming of the device.

In general, the invention comprises a projecting wheel rotating within a casing, said 20 wheel having one or more projectile supply passages terminating at the rim of the wheel in propelling shoulders and the casing having a guide groove extending from the plane of said passages to a discharge passage located in a different plane, the propelling 25 shoulder usually extending across the rim of the wheel between said two planes so as to propel the projectiles throughout said groove.

30 Other features will be made clear as the specification proceeds, attention being now directed to the accompanying drawings, illustrating the invention embodied in practical form and in which Figure 1 is a plan view of the device, broken away to show more clearly the adjustable joint for the barrel; Fig. 2 is an edge view of the same; Fig. 3 is a cross sectional view taken through the casing and projecting wheel; 35 Fig. 4 is a diagrammatic view of the guide groove construction; Figs. 5 and 6 are sectional views taken substantially on the planes of lines 5—5 and 6—6 of Fig. 3; Fig. 7 is a broken detail view of the propelling 40 shoulder on the projecting wheel.

The projecting member is designated 10 and as indicated, is in the nature of a balance wheel, designed to be rotated at great velocity. It is shown keyed on an upright 45 shaft 11, having a gear 12 on its lower end for engagement by the drive gear of an electric motor or the like, suitable means, such as the ball bearings 13 being provided to insure free and accurate running of the parts.

55 In the upper side of the projecting

member there is provided a chamber 14 forming a magazine for the projectiles, which may be ordinary steel balls, and radiating from this chamber are a plurality of passages 15 terminating at the rim of the wheel in the drive shoulders 16, said shoulders being located immediately at the ends of the radial passages, as shown, or somewhat to the rear of such ends.

Surrounding the wheel is a casing 17 having a projectile guiding groove in the inner face thereof, said groove consisting of an upper receiving portion 18 disposed in the plane of the projectile passages, a discharge portion 19, disposed in a lower plane and terminating in a discharge passage 20 and an intermediate portion 21 extending on an incline from the upper plane down to the lower plane. Fig. 4 is a plan of this groove, the lower half in this view being 60 a continuation of the right hand end of the upper half, from which it will be seen that the upper entrance portion 18 of the groove extends in a horizontal plane for approximately a complete turn, that the incline 21 65 makes practically one complete turn and that the lower discharge portion 19 extends in a horizontal plane for about three-quarters of a turn, so that the projectiles in traversing this groove make something over 70 two turns of the casing. Approximately at the junction of the entrance portion 18 with the downwardly inclined portion 21 there is shown provided an enlargement 22 in the groove, having a downwardly inclined wall 75 80 85 90 95 23 for starting the balls or bullets on their downward course. It is obvious that more than one outlet and one entrance may be provided in the entrance and discharge portions respectively.

The bullets may be suitably fed into the magazine, as through a supply tube 24. A conical distributor 25 is shown, centrally located in the magazine, for starting the bullets into the radial supply passages and an annular rim 26 is shown overlying the mouths of such passages for confining the bullets to said passages. The entrances to the passages may be opened out or widened laterally as indicated at 27 in Fig. 5, to 100 facilitate entrance of the balls thereinto. The cups thus formed, are shown extended rearwardly, the direction of rotation considered, forming pockets holding the balls for an instant while picking up the speed of 105 110

the rotating wheel. As the balls take up the speed of the wheel, they roll or slide out the radial passages, into the receiving portion of the guide groove and are then 5 propelled by the drive shoulders 16 which are located at the rearward sides of such passages. These drive shoulders extend downwardly across the rim of the wheel to the plane of the lower discharge passage, as 10 shown in Figs. 3 and 7 so as to propel the projectiles throughout their passage along the groove, the projectiles sliding or rolling downward across the face of the shoulder during such passage, as will be clear from 15 Fig. 7.

The projectiles leave the discharge passage at high velocity. By traversing the casing on its axis the fire may be directed laterally in any direction and by providing 20 an adjustable barrel like that illustrated in Figs. 1 and 2 the angle of fire, in elevation, may be changed. This barrel, designated 25 28, is shown connected by a ball and socket joint 28' with the end of the discharge passage, it being trunnioned at 29 and adapted to be shifted by a worm 30, operating on a sector 31, on the barrel. A handle 32 is shown provided for manually operating the worm.

30 The rapidity of fire may be controlled by varying the speed of the projecting wheel and the rate of supply of projectiles and the velocity also is controlled by this varying of the speed.

35 I claim:

1. A centrifugal gun comprising a rotatable projecting member having a substantially central magazine, a projectile passage extending therefrom to the rim of the member and a propelling shoulder adjacent the 40 end of said passage, and a casing surrounding the projecting member having a projectile receiving groove horizontally arranged within the casing with an entrance in the 45 plane of the projectile passage a discharge groove horizontally arranged within the casing and an interconnecting groove for said horizontal grooves, said propelling shoulder on the projecting member extending from the plane of the entrance end of the projectile receiving groove to the plane of the discharge end thereof.

2. A centrifugal gun comprising a rotatable projecting member having a substantially central magazine, a projectile passage extending therefrom to the rim of the member and a propelling shoulder adjacent the 55 end of said passage, and a casing surrounding the projecting member having a projectile receiving groove with an entrance in the plane of the projectile passage and terminating in a tangential discharge bore disposed in a different plane, said groove having an enlargement therein in the plane of 60 such entrance portion and inclined in the

direction of the discharge portion thereof, said propelling shoulder on the projecting member extending from the plane of the entrance end of the projectile receiving groove to the plane of the discharge end thereof. 70

3. A centrifugal gun comprising a rotatable projecting member having a substantially central magazine and a projectile passage extending therefrom to the rim of the member, a casing surrounding the projecting member provided with a projectile guiding groove horizontally arranged within the casing having a receiving portion in the plane of said passage, a horizontally arranged discharge portion in another plane 75 and an inclined portion connecting the two, a discharge passage at the end of said discharge portion of the guiding groove and a propelling shoulder on the projecting member adjacent the end of the projectile passage extending from the entrance plane of said groove to the plane of the discharge passage.

4. A centrifugal gun comprising a rotatable projecting member having a substantially central magazine and a projectile passage extending therefrom to the rim of the member, a casing surrounding the projecting member provided with a projectile guiding groove having a receiving portion in the plane of said passage, a discharge portion in another plane and an inclined portion connecting the two, a discharge passage at the end of said discharge portion of the guiding groove, a propelling shoulder on the projecting member adjacent the end of the projectile passage extending from the entrance plane of said groove to the plane of the discharge passage, an adjustable barrel at the end of the discharge passage, and means 95 for shifting said barrel. 100

5. A centrifugal gun comprising a rotatable projecting member having a substantially central magazine and a projectile passage extending therefrom to the rim of the member, a casing surrounding the projecting member provided with a projectile guiding groove having a receiving portion in the plane of said passage, a discharge portion in another plane and an inclined portion 110 connecting the two, a discharge passage at the end of said discharge portion of the guiding groove and a propelling shoulder on the projecting member adjacent the end of the projectile passage extending from the entrance plane of said groove to the plane of the discharge passage, a barrel having a ball and socket joint with the end of the discharge passage, and means for rocking 115 said barrel at said joint. 120

6. A centrifugal gun comprising a rotatable projecting member having a substantially central magazine and projectile passages extending radially therefrom to the rim of the member, the entrances to said pas- 130

sages being enlarged rearwardly to form projectile holding pockets, a confining flange overlying said entrance pockets, means adjacent the flange for distributing projectiles to said pockets, propelling shoulders adjacent the ends of the passages, and a casing surrounding the projecting member having

a guide groove in line with the passages a second parallel groove terminating in a discharge passage and a groove for connecting 10 said grooves.

In testimony whereof I affix my signature.

WILLIAM W. CASE.
